UNITED STATES PATENT OFFICE.

CHARLES J. HENDRICKSON, OF NEW YORK, N. Y., ASSIGNOR TO WESTERN ELECTRIC COMPANY, INCORPORATED, OF NEW YORK, N. Y., A CORPORATION OF NEW YORK.

CENTRIFUGAL GOVERNOR.

Application filed September 28, 1921. Serial No. 503,842.

To all whom it may concern:

Be it known that I, CHARLES J. HENDRICKSON, a citizen of the United States, residing at New York, in the county of New York,

5 State of New York, have invented certain new and useful Improvements in Centrifugal Governors, of which the following is a full, clear, concise, and exact description.

This invention relates to centrifugal friction retarded governors and its object is the provision of a governor which will operate up to a predetermined maximum speed but cannot be forced beyond that speed by the application of additional driving force.

10 The present invention is particularly applicable to calling devices such as shown in United States Patent No. 1,161,854, issued to O. F. Forsberg November 30, 1915, for use on subscriber's telephone sets in automatic telephone systems. Such a device, as is quite generally known, comprises a rotatable dial which the calling subscriber operates with his finger. The operation consists, usually, of rotating the dial a variable 20 angular distance until the subscriber's finger encounters a stop which is especially provided for the purpose, whereupon he releases the dial permitting it to return to its normal position. This operation is repeated 25

30 a number of times corresponding with the number of digits in the called subscriber's number, and each time the calling subscriber inserts his finger in a particular finger hold in the dial corresponding with the particular 35 digit, or, in other words, with the number of electrical impulses he desires to send. Upon each return movement of the dial a suitable mechanism is operated whereby the subscriber's line circuit is interrupted one or 40 more times according to the digit dialed. The time rate at which the circuit is interrupted is of necessity very accurately regulated, and this regulation is accomplished by a frictionally retarded centrifugal governor.

45 Any appreciable increase above normal in the rate at which the circuit is interrupted is likely to result in a wrong connection.

It has been found in practice that some subscribers, in spite of instructions to the 50 contrary, try to expedite their connections by forcing the dial in its backward movement; which action instead of accomplishing this object, usually secures a wrong connection. A number of attachments for calling dials have heretofore been proposed to pre-

vent forcing of the dial; but each of them has added something to the cost of the calling device, and for that reason they have not been generally used.

The present invention accomplishes the object set forth and adds little or nothing to the cost of the calling device for the reason that no additional parts are required.

A governor in accordance with this invention consists preferably of a stationary member having an internal annular surface, and a rotatable member, including pivoted fly-weights, which are adapted to frictionally engage the internal annular surface of the stationary member when the governor is 60 rotated at its predetermined maximum speed. The fly-weights are preferably provided with friction studs which are so located with respect to the pivotal points of their respective fly-weights that any force 65 tending to rotate the rotatable member in addition to such force as is necessary to drive the rotatable member at its predetermined maximum speed will be completely 70 or almost completely opposed by the frictional retarding force of the governor.

75 For a more complete description of the invention, reference will now be had to the accompanying drawing in which Fig. 1 is a plan view of a governor constructed in accordance with this invention; Fig. 2 is a cross sectional view taken along the line 2-2 of Fig. 1; Fig. 3 is a cross-sectional view of the ratchet mechanism taken along the line 3-3 in Fig. 2; and Fig. 4 is a diagrammatic 80 view corresponding with Fig. 1 illustrating, graphically, the resolution of forces operating in the governor.

85 The structure shown in Figs. 1 and 2 is somewhat similar to that shown and described in the copending application of Henry F. Dobbin, Serial No. 428,695, filed December 6, 1920. It comprises a spindle which is coaxial with and journaled at one 90 end in the stationary cup-shaped member 2 and at the other end in a suitable bearing which is not shown. Pinion 3 is revolubly mounted on spindle 1 and is provided with ratchet teeth 4 which are adapted to engage pawl 5. The plate 6 is rigidly secured to 95 spindle 1 and is accordingly rotatable therewith. Pawl 5 is pivotally mounted on plate 6 and held in engagement with the ratchet teeth 4 by a suitable spring which is not shown.

Fly-weights 7 are pivotally mounted on plate 6 by means of suitable pins 8 and are free to move outwardly in response to centrifugal force. Each fly-weight 7 is provided with a friction stud 9 which is adapted to engage the internal annular surface of the cup-shaped member 2.

Each fly-weight is also provided with a pliable arm 10, which in the present instance 10 is secured thereto by being inserted in a slot 11 in the fly-weight. The arms 10 are each shown provided with a pointer 12 which registers with a calibrated scale on its respective fly-weight.

15 A retractile spring 13 is connected between the pliable arms 10 and passes through an aperture 14 in spindle 1. This spring is intended to oppose the centrifugal force developed in the fly-weights when the 20 governor is operated. By bending either or both of the pliable arms 10 toward the designation "F" on their respectively associated scales, the tension of spring 13 is increased and accordingly the speed at which 25 the governor will operate is increased. Bending the pliable arms toward their respective scale designation "S" will, of course, decrease the tension in spring 13 and accordingly the speed at which the governor may 30 be operated is decreased.

When pinion 3 is rotated in the counter-clockwise direction, as indicated in Fig. 1, pawl 5 is engaged by the ratchet teeth 4, and the plate 6 together with spindle 1, fly- 35 weights 7 and associated parts are rotated in the same direction.

It will be noted that the friction studs 9 move in advance of the pivots 8 of their respective fly-weights.

40 The governor is adjusted to run at a predetermined maximum speed by tensioning the retractile spring 13. At the predetermined maximum speed, the centrifugal force is sufficient to throw the fly-weights outwardly in opposition to the retractile spring, to such an extent that the friction studs 9 just fail to make contact with the internal annular surface of the cup-shaped member 2. The slightest additional increase in speed 45 50 is sufficient to cause the friction studs to engage the aforementioned internal annular surface.

Fig. 3 will now be referred to and it will be assumed that the governor is rotating at 55 a speed which is just a trifle in excess of its maximum predetermined speed. Now any tendency to increase the speed of the governor is, of course, due to a corresponding increase in the driving force, and this increased driving force acts on the friction stud along the line B-C. If the angle between the line B-C and the radial line A-D be assumed to have a value α , then 60 65 when $\tan \alpha$ is equal to the coefficient of friction between the friction stud and the in-

ternal annular surface of the cup-shaped member, any increase in the driving force applied to the governor, in excess of that required to drive it at its predetermined maximum speed, will be overcome by an equal retarding force. This condition is expressed by the following equation:

$$\tan \alpha = Z$$

where

$$Z = \text{coefficient of friction}$$

$$\alpha = \text{angle indicated in Fig. 3}$$

Now assume an arbitrary increase in driving force beyond that necessary to drive the governor at its maximum predetermined speed and let such increase be represented in direction and intensity by the line BE. It is evident that the force BE has a normal component BD and a tangential component BF, and the latter represents the increase in tangential force tending to increase the speed of the governor. The tangential frictional retarding force acting on the stud 9 is equal to the product of the normal force BD and the coefficient of friction. Then if such product, which is represented as ED, is equal and opposite to the force BF, it is obvious that the two forces are balanced and there can be no increase in speed. This condition may be expressed by the following formula:

$$BD \times Z = ED = \text{retarding force}$$

and since

$$BD \times \tan \alpha = BF =$$

increase in tangential driving force

and as

$$ED = BF$$

therefore

$$BD \times \tan \alpha = BD \times Z$$

and

$$\tan \alpha = Z$$

If the studs 9 are made of cork and the cup-shaped member 2 is made of brass, the coefficient of friction is approximately .36 and the angle α would, therefore, be approximately $19^\circ 50'$ because the tangent of that angle is approximately .36. With the studs 9 properly located in accordance with the theory propounded above, the speed of the governor cannot be increased beyond the predetermined maximum and experiment has shown that it will run smoothly in spite of any inordinate driving force.

If the studs are so located that the tangent of the angle α exceeds the coefficient of friction, the governor can be forced beyond its predetermined maximum speed, but if the deviation is slight, the increase in speed is very small as compared with the extra force exerted. If the studs are so located that the tangent of the angle α is less than the coefficient of friction, the governor will slow down whenever an excessive driv-

ing force is applied to it. This deviation, if slight, does not appreciably affect the accuracy of the governor.

It is commercially impracticable to locate the friction studs exactly at the ideal point whereby the governor is entirely unaffected by an excessive driving force, but a small deviation from the ideal point, such as would have to be allowed in commercial practice, does not sensibly affect the ultimate result.

It has been found that the friction studs can be located on a commercial basis with a degree of accuracy well within the requirements for use in calling devices for automatic telephone practice.

As a matter of convenience, the angle α is referred to in the claims, hereinafter, as the angle of application.

20 What is claimed is:

1. In a centrifugal governor, a stationary member having an annular surface, a rotatable member comprising a pivoted fly-weight, said fly-weight being arranged to frictionally engage the annular surface of said stationary member at a point in advance of the pivotal point of said fly-weight, the angle of application of the driving force being such that the tangent of said angle is substantially equal to the coefficient of friction between said fly-weight and said stationary member.

2. A centrifugal governor comprising a stationary member having an internal annular surface, a rotatable spindle in co-axial alignment with said stationary member, said rotatable spindle comprising a pair of pivoted fly-weights, a friction stud on each of said fly-weights arranged to engage said internal annular surface, a pliable arm attached to at least one of said fly-weights, a

retractile spring for restraining said fly-weights against centrifugal force, said retractile spring being attached to said pliable arm, means for imparting rotary motion 45 from said spindle to said fly-weights in only such direction that said friction studs move in advance of the pivotal points of their respective fly-weights, the angle of application of the driving force being such that the tangent of said angle is substantially equal to the coefficient of friction between the fly-weights and the stationary member.

3. A centrifugal governor comprising a stationary member having an annular surface, a rotatable member comprising a fly-weight, a friction stud for frictionally engaging said annular surface and so placed upon the fly-weight that any driving force in excess of that required to maintain a predetermined speed of operation is substantially opposed by the frictional retarding force.

4. A centrifugal governor comprising a stationary member having an internal annular surface, a rotatable member comprising a fly-weight, a friction stud for frictionally engaging said annular surface and so placed upon the fly-weight that any driving force in excess of that required to maintain a predetermined speed of operation is substantially opposed by frictional retarding force, and a retractile spring for said fly-weight adjusted to balance the centrifugal force operating thereon at said predetermined speed so that said friction stud just fails to make contact with the internal annular surface of said stationary member.

In witness whereof, I hereunto subscribe my name this 24th day of September, A. D. 1921.

CHARLES J. HENDRICKSON.
